(57) **CLAIM**

The ornamental design for a ceiling fan with light, as shown and described.

DESCRIPTION

FIG. 1 is a front, left, top perspective view of a ceiling fan with light, showing my new design;

FIG. 2 is a rear, right, bottom perspective view thereof;

FIG. 3 is a front elevational view thereof;

FIG. 4 is a rear elevational view thereof;

FIG. 5 is a left side view thereof;

FIG. 6 is a right side view thereof;

FIG. 7 is a top plan view thereof;

FIG. 8 is a bottom plan view thereof;

FIG. 9 is an enlarged view of detail 2 in FIG. 9;

FIG. 10 is an enlarged view of detail 7 in FIG. 10; and,

FIG. 11 is an enlarged view of detail 8 in FIG. 11.

Broken lines illustrate portions of the ceiling fan with light that form no part of the claimed design.
